(57) **CLAIM**

The ornamental design for a solar-powered roadway light, as shown and described.

DESCRIPTION

FIG. 1 is a perspective view of a solar-powered roadway light according to the present invention.

FIG. 2 is a top view of the solar-powered roadway light illustrated in FIG. 1.

FIG. 3 is a bottom view of the solar-powered roadway light illustrated in FIG. 1.

FIG. 4 is a right side view of the solar-powered roadway light illustrated in FIG. 1.

FIG. 5 is a left side view of the solar-powered roadway light illustrated in FIG. 1.

FIG. 6 is a front view of the solar-powered roadway light illustrated in FIG. 1; and,

FIG. 7 is a rear view of the solar-powered roadway light illustrated in FIG. 1.

The broken lines shown on the drawings form no part of the claimed design.
